UNITED STATES PATENT OFFICE

WADE H. REICHARD, OF ROCHESTER, NEW YORK, ASSIGNOR TO GENERAL RAILWAY SIGNAL COMPANY, OF ROCHESTER, NEW YORK

AUTOMATIC TRAIN-CONTROL SYSTEM

Application filed July 15, 1929. Serial No. 378,323.

This invention relates in general to automatic train control, and has more particular reference to an electro-magnetic valve of improved type, particularly adapted for use in such systems.

In train control systems such as disclosed in detail in the Reichard application 358,577, filed April 27, 1929, there is employed an electro-magnetic valve which, when energized, prevents an automatic application of the brakes but which, when de-energized, vents the air line or equivalent part to cause an automatic brake application.

One of the objects of this invention is to provide an electro-magnetic valve, for train control systems, having an improved core structure which facilitates the manufacture and the assembly of the same and permits ready adjustment of the magnetic characteristics thereof.

Another object of this invention is to provide an improved connection between an electrically operated spindle and the stem of a valve operated by the spindle.

A further object of the invention is to provide an improved adjusting means for adjusting the position of a valve stem relatively to an operating spindle therefor.

Further objects, purposes and characteristic features will appear as the description progresses, reference being made to the accompanying drawings showing, solely by way of example, and in no manner in a limiting sense, one form which the invention can assume. In the drawing:

Fig. 1 is a diagrammatic view of a train control system employing the improved electro-magnetic valve of this invention.

Fig. 2 is a side elevation, with parts shown in section, of the valve according to this invention.

Fig. 3 is a sectional view on lines 3-3 of Figs. 2 and 4.

Fig. 4 is a top plan view of the valve.

Fig. 5 is a sectional view on line 5-5 of Fig. 2.

Fig. 6 is a sectional view on line 6-6 of Fig. 2.

Referring first to Fig. 1, there is here shown, in a wholly diagrammatic manner, a

train control system such as disclosed more in detail in the Reichard application above referred to. This system includes a receiver R, carried by the car and inductively cooperating with an inductor I, which latter is controlled in accordance with traffic conditions to variously influence the receiver.

The receiver has two primary windings P which are energized from a source A of alternating current and at times induce currents in two receiver secondary windings S, which latter energize coils C on the valve V to thereby maintain the valve member 1 seated, to prevent the venting of a brake valve actuator cylinder 2 to atmosphere through a port 3. In this manner, under safe traffic conditions, the valve member is maintained seated and the brakes are held off, while under unsafe conditions, coils C are de-energized, thereby to permit valve member 1 to open and vent cylinder 2 and cause an automatic brake application.

No further description of the parts shown in Fig. 1 is deemed necessary, or desirable, since the present invention more particularly involves the structural details of the valve V.

Referring now to the other figures of the drawing, the valve V includes a face plate P, having a shelf-like extension S at one side, and having a core and coil carrying bracket B fastened to the other side by means of screws 4 or the like.

The bracket B has two plate-like members 5, which bear against one face of the plate P, and an outer plate-like member 6 spaced from members 5. Projecting outwardly from member 6 are two arms 7 for a purpose to be later described.

The core structure of the valve, built up of laminæ, is in the general form of a horse shoe and comprises two separate leg members L, and a back strap BS. Each of the leg members L is rigidly bolted to the bracket B as by connecting means 8. Sleeved over the free ends of the legs L of the core, are coils 9 which bear at one end against plate member 6.

Clamped to bridge across the outer ends of the legs L, is the back strap BS, which is built up of a plurality of fibre strips 10, with

laminæ 11 of transformer iron clamped between the strips 10 as by bolts 12 whereby to facilitate the ready adjustment of the cross section of the back strap by adding or removing laminæ therefrom, to obtain the desired magnetic characteristics of the core structure.

A clamp member 13 is clamped over the back strap BS, and fastened to the ends of arms 7 by means of screws 14, whereby clamp 13 can be tightened into place to tightly draw the back strap against the ends of the legs L and securely hold the coils 9, which are substantially flush with the ends of the legs, clamped between the back strap BS and the plate 6 of bracket B.

Pivoted at one end in a boss 15 of the bracket B, and at the other end in a bearing 16 carried by a downwardly projecting portion of the shelf S, is a spindle 17, to which is fastened an armature 18 positioned to rock between opposite side faces of the core legs L, these legs L being offset laterally, as shown most clearly in Fig. 6, to thus accommodate 25 the armature 18.

Fastened to spindle 17, is a carrier member 19, to which is fastened one end of a U-shaped leaf spring 20, as by means of screws 21, the other end of spring 20 being received in a slot 22 in spindle 17 and free to move a limited amount within such slot.

Bearing against the free end of spring 20, adjacent the spindle 17, is the end of a stem 23 of valve member 1, which is biased by 35 means of a coil spring 24 to open position, to thereby vent the passage 25, which is connected to the cylinder 2, for example, of Fig. 1 to atmosphere through the port 3.

Valve 1 is carried in a housing 26 which is 40 screwed into a carrier 27 which is cylindrical in form and rotatably received in shelf S. As best seen in Fig. 2, housing 26 is eccentrically carried in the member 27, and can be rigidly clamped therein by means of the split 45 coupling 28.

Carrier 27 is clamped in adjusted position by means of a retaining member 29 which fits over the edge of 27 and can be tightened down by a screw 30. Member 27 is also clamped in 50 place by a retaining member 31, beneath which is a toothed adjusting member 32 having teeth 33 for meshing with teeth 34 on the adjacent portion of the periphery of member 27, member 32 being held against turning, 55 when clamped down, by means of a shoulder 35 on the shelf member S.

By releasing clamp members 29 and 31 and then removing toothed member 32, carrier 27 can be turned to thereby adjust the point 60 of contact between the end of the valve stem 23, and the spring 20, to the desired position. By then replacing toothed member 32 in its seat, and reclamping members 29 and 31, the 65 above desired adjustment is readily and securely retained.

The coil spring 24 is strong enough to operate through valve stem 23, spring 20, member 19 and spindle 17 to move armature 18 to retracted position when coils 9 are de-energized. On energization of coils 9, however, 70 armature 18 is attracted to the leg members L of the core structure to thereby rock spindle 17 and member 19 connected thereto whereby to move spring 20 upwardly so as to close the valve member 1 and prevent venting of air 75 pressure and thus prevent an automatic brake application. Spring 20 is adjusted so as to bias valve member 1 to closed position, when armature 18 is in attracted position. Any tendency of spring 20 to open up and not 80 move away from stem 23 when armature 18 moves to retracted position, is prevented by the upper face of slot 22 in spindle 17, which positively moves the free end of spring 20 away from valve stem 23.

The above described structure thus provides an improved core structure which can be cheaply and readily manufactured, assembled and adjusted; a connection between the armature actuating spindle and the actuated air control valve which is positive in action, simple in construction and practically immune from failure; and a simple and readily operated adjusting means for adjusting, and then clamping in adjusted position, the air valve relatively to its actuating spring member.

The above rather specific description of a device embodying this invention, is given solely by way of illustration, and is not intended, in any manner whatsoever, in a limiting sense. Obviously, this invention can assume many different physical forms, and is susceptible of various modifications, and all such forms and modifications are desired to be included by this invention, as come within the scope of the appended claims.

Having described my invention, I now claim:—

1. In an electro-magnetic valve for train control systems, in combination, a valve for controlling an air line, a U-shaped field core comprising separate laterally offset legs and a separate back yoke butted, and clamped, against ends of said legs and an armature pivoted to operate between and against side faces of said offset legs and actuate said valve.

2. In an electro-magnetic valve for train control systems, in combination, a valve for controlling an air line, an armature connected to actuate the valve, and a U-shaped field core comprising separate laterally offset legs and a separate back yoke butted, and clamped, against ends of said legs, said back yoke including a plurality of spaced longitudinal strips of non-magnetic material with longitudinal bundles of laminæ of magnetic material clamped therebetween.

3. In an electro-magnetic valve for train control systems, in combination, a valve for

controlling an air line, an armature connected to actuate the valve, a U-shaped field core comprising separate laterally offset legs and a separate back yoke butted, and clamped, against ends of said legs, a spring biasing the valve to open position, a spindle carrying said armature, a slot in the spindle, a looped leaf spring fastened at one end to the spindle and loosely received at its other end in the slot in the spindle, and a stem for the valve resting on the leaf spring.

4. In an electro-magnetic valve for train control systems, in combination, a valve for controlling an air line, an armature connected to actuate the valve, a U-shaped field core comprising separate laterally offset legs and a separate back yoke butted, and clamped, against ends of said legs, said back yoke including a plurality of spaced strips of non-magnetic material with lamina magnetic material clamped therebetween, a spring biasing the valve to open position, a spindle carrying said armature, a slot in the spindle, a looped leaf spring fastened at one end to the spindle and loosely received at its other end in the slot in the spindle, and a stem for the valve resting on the leaf spring.

5. In an electro-magnetic valve for train control systems, in combination, a valve for controlling an air line, an armature connected to actuate the valve, a U-shaped field core comprising separate laterally offset legs and a separate back yoke butted, and clamped, against ends of said legs, a spring biasing the valve to open position, a spindle carrying said armature, a slot in the spindle, a looped leaf spring fastened at one end to the spindle and loosely received at its other end in the slot in the spindle, a stem for the valve resting on the leaf spring, a housing for the valve eccentrically fixed in an adjusting member, and releasable toothed clamp means for the adjusting member for clamping the adjusting member in position.

45 6. In an electro-magnetic valve for train control systems, in combination, a valve for controlling an air line, an armature connected to actuate the valve, a U-shaped field core comprising separate laterally offset legs and a separate back yoke butted, and clamped, against ends of said legs, said back yoke including a plurality of spaced strips of non-magnetic material with magnetic material clamped therebetween, a spring biasing the valve to open position, a spindle carrying said armature, a slot in the spindle, a looped leaf spring fastened at one end to the spindle and loosely received at its other end in the slot in the spindle, a stem for the valve resting on the leaf spring, a housing for the valve, and a toothed rockable adjusting member eccentrically receiving the housing, whereby to adjust the point of contact between the valve stem and the leaf spring.

65 7. In an electro-magnetic valve for train

control, a plate, a bracket fixed to one face of the plate, substantially parallel, laterally offset, magnetic core legs fixed to the bracket, a back yoke, a clamp fastened to the bracket and clamping the back yoke against, and bridging the ends of, the legs, a projecting shelf on the bracket, coils on the legs and clamped between the projecting shelf and the back yoke and an armature positioned to operate between the offset legs.

8. In an electro-magnetic valve for train control, a plate, an angle shelf in the form of a downwardly extended elbow on one face of the plate, a bracket fixed to the other face of the plate, substantially parallel, laterally offset, magnetic core legs fixed to the bracket, a back yoke, a clamp fastened to the bracket and clamping the back yoke against, and bridging the ends of, the legs, a projecting shelf on the bracket, coils on the legs and clamped between the projecting shelf and the back yoke, a spindle passing through the plate and pivoted in the bracket and the lower arm of the angle shelf, and an armature on the spindle rockable between, and against opposite side faces of, said core legs.

9. In an electro-magnetic valve for train control, a plate, an angle shelf in the form of a downwardly extended elbow on one face of the plate, a bracket fixed to the other face of the plate, substantially parallel, laterally offset, magnetic core legs fixed to the bracket, a back yoke, a clamp fastened to the bracket and clamping the back yoke against, and bridging the ends of, the legs, a projecting shelf on the bracket, coils on the legs and clamped between the projecting shelf and the back yoke, a spindle passing through the plate and pivoted in the bracket and the lower arm of the angle shelf, an armature on the spindle rockable between, and against opposite side faces of, said core legs, an air vent valve adjustably carried by the angle shelf, and a resilient operative connection between the valve and the spindle.

In testimony whereof I affix my signature.
WADE H. REICHARD.
